UNITED STATES PATENT OFFICE

2,577,665

FOUNTAIN COMB

Stanley A. Rypel and Rupert Rypel,
Milwaukee, Wis.

Application August 7, 1947, Serial No. 766,944

1 Claim. (Cl. 132—13)

1

Our invention refers to fountain combs for treatment of the hair and scalp to evenly distribute any type of liquid or medicated solution automatically during the process of combing.

The specific object of our invention is to provide a simple and effective hollow shell, having a reservoir chamber at one end and a distributing chamber at the opposite end, the said chambers having a communicating port therebetween.

The lower edges of the shell are closed to form a distributing chamber by a slotted backbone of a comb. The distributing chamber or shank portion of the shell is, in the operation, tilted slightly downward, whereby fluid from the reservoir chamber is delivered into the distributing chamber through the port therebetween and the fluid is thus discharged to the patient's scalp from the comb teeth.

With the above and other objects in view, which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Figure 1 represents a sectional elevation view of a fountain comb embodying the features of our invention, the section being indicated by line 1, 1 of Figure 2.

Figure 2 is a top plan sectional view of the same, the section being indicated by line 2, 2 of Figure 1.

Figure 3 is a cross sectional view through the comb, the section being indicated by line 3, 3 of Figure 1.

Figure 4 is another cross sectional view of the comb upon a different plane, the section being indicated by line 4, 4 of Figure 1.

Figure 5 is a sectional end view of the comb flattened out, wherein the same may be folded upon itself to develop "bleeds."

Figure 6 is another cross sectional view of a comb, wherein the same may be fabricated from two sections slightly spaced apart.

Figure 7 is a similar cross sectional view of the two part comb, having fitted therebetween a layer of porous material.

Figure 8 is a still further modified form of

2

comb, wherein the same is fabricated from a single porous section.

Figure 9 is an enlarged sectional elevation view of a modified form of valve for introducing fluid into the comb shell.

Figure 10 is a cross sectional view through the same, the section being indicated by line 10, 10 of Figure 9.

Figure 11 is an end view of the discharge nozzle of the fluid container; and

Figure 12 is another cross sectional view through the valve mechanism, the section being indicated by line 12, 12 of Figure 9.

Referring by characters to the drawings, 1 indicates a rectangular shell, having at its shank end a fluid reservoir chamber 2, and a fluid distributing chamber 3 at the opposite end.

The two chambers are separated by a partition 4, the same being stopped below the top edges of the shell, to form a discharge port 4' communicating with the chambers.

The bottom of the distributing chamber 3 is closed by a comb backbone 5, 5, which backbone forms the bottom of said chamber, its two parts being slightly spaced apart to develop a slot 6 therebetween. As indicated in Figures 3 and 5, the comb is formed from a flat blank, folded upon itself, at the central portion of said blank intersecting the comb tooth ends.

The shank or reservoir portion of the shell 1 is provided with a fluid filling opening 7, which communicates with the reservoir chamber 2, and the filling opening is closed by a screw plug 7'.

As indicated in Figure 6 of the drawings, the comb is fabricated from like comb layers 6' 6' and as shown in Figure 7, a thin porous sheet 6'' can be placed between these sections for permitting liquid to seep therethrough.

Referring to Figure 8 of the drawings, another form of comb is illustrated, wherein the same is molded from a porous fiber B.

As illustrated in Figures 9 to 12 inclusive of the drawings, the filling opening 7, in some instances, may be formed with an enlarged recess 7'' threaded at its outer end.

An externally threaded sleeve 8 is fitted into the mouth of the recess, the internal bore of which sleeve 8 is also threaded and adapted to receive an exteriorly threaded nozzle 8' of a fluid container tube, as best shown in Figure 9 of the drawing.

The sleeve 8 has seated at its inner end a valve 9, which is held against its seat by a coil spring 10, interposed between the base of the recess 7'' and the valve member 9.

The valve member 9 is provided with a stem,

11, having a crowned end, and said stem carries a pin 11', which pin is slidably guided in grooves 8" formed in the sleeve 8.

The valve member 9 is also guided by an anchor pin 12, the said pin being carried by the sleeve, and is extended through a slot 12' formed in the valve stem 11.

The nozzle 8' of the container tube is formed with a cupped end recess 11" and a discharge aperture 13, which aperture is branched about the recess.

From the foregoing description it is apparent when the container nozzle is inserted about the valve stem 11 and in threaded engagement with the sleeve, it is rotated with reference to its threaded connection, and the valve 9 will be forced open against its spring pressure, whereby the fluid from the container tube is discharged into the reservoir 2, and obviously, when the container is removed from its threaded engagement with the valve equipment, the same will be closed by the spring 10.

The fluid container tube is for the purpose of refilling the reservoir chamber 2, and when its nozzle 8' is inserted into the filling opening 7, it opens valve 9, whereby the fluid is discharged from the container aperture 13 into the reservoir of chamber 2.

From the foregoing description, with reference to the fountain comb assemblage, it is apparent should a party desire to use the comb, the shank or handle end may be tilted upwardly, whereby a small quantity of the fluid contained in the reservoir chamber is delivered to the distributing chamber, and thereafter this volume of fluid will gradually seep down into or about the comb teeth for uniform distribution to the hair and scalp.

We claim:

A fountain comb comprising a shell having a reservoir chamber at one end provided with a filling opening, a partition extending transversely of the reservoir chamber terminating a slight distance from the top edge of the shell to form a discharge port, a comb backbone and teeth on the backbone, said backbone being secured to the bottom edge of the shell beyond the reservoir chamber to close said bottom end and form with the shell a fluid distributing chamber, said discharge port for the reservoir chamber opening into the fluid distributing chamber, whereby upon an upward tilt of the reservoir chamber fluid will be discharged into the distributing chamber through the port, said backbone having a longitudinally extending slot opening into the distributing chamber and out through the lower edge of the backbone at said comb teeth.
